UNITED STATES PATENT OFFICE.

OLIN S. FELLOWS, OF MIDDLETOWN, NEW YORK.

MEANS FOR REMOVING SUPERFLUOUS SOLDER FROM SHEET-METAL CANS.

SPECIFICATION forming part of Letters Patent No. 727,324, dated May 5, 1903.

Application filed October 31, 1902. Serial No. 129,518. (No model.)

To all whom it may concern:

Be it known that I, OLIN S. FELLOWS, a citizen of the United States, residing at Middletown, Orange county, and State of New York, have invented certain new and useful Improvements in Means for Removing Superfluous Solder from Sheet-Metal Cans, of which the following is a specification, sufficient to enable others skilled in the art to which the invention appertains to make and use the same.

My improvements relate to machines for removing superfluous solder from the exterior of tin cans; and the invention consists, essentially, in the construction and arrangement of parts hereinafter described and claimed specifically.

A distinguishing feature of my present construction consists in the use of a convex guiding-surface for the cans, in conjunction with an opposed flexible can-forwarding surface, whereby the cans are positively brought into engagement with the flexible forwarding-surface, subjected to a uniform degree of pressure, and properly spaced for presentation to the solder-removing mechanism. I thus not only prevent bunching, (the contact of one can with another,) but also sustain the cans more firmly in position against the resistance afforded by the solder-removing mechanism, at the same time compensating for any slight variation from the standard in the diameter or configuration of the cans individually.

Another feature of my present construction consists in so arranging the parts that the machine is practically reversible—that is to say, the cans may be fed in at either end, as desired, according to the direction of motion imparted to the can-forwarding belt.

In the accompanying drawings, Figure 1 is a front elevation of the machine; Fig. 2, a sectional detail, upon an enlarged scale, showing the duplex blast-nozzle; Fig. 3, a plan of the machine. Fig. 4 is a detail view of one of the spring-jaws with which the convex can-guiding surface is provided. Figs. 5, 6, and 7 are respectively a top view, front and side elevations, of one of the standards supporting the convex can-guiding surface and top rail. Fig. 8 is a rear elevation of the machine. Fig. 9 is a plan of the machine with the covers removed; Fig. 10, an eleva-

tion of the left-hand end of the machine; Fig. 11, a vertical section on line 11 11, Fig. 3; Fig. 12, a vertical longitudinal section on plane of line 12 12, Fig. 3; Fig. 13, a sectional elevation, upon an enlarged scale, upon plane of line 13 13, Fig. 3. Figs. 14 and 15 are respectively top and side views of the adjustable standard shown in Fig. 13; Fig. 16, a longitudinal sectional elevation on plane of line 16 16, Fig. 3; Fig. 17, a sectional elevation of the retarding-wheel, showing means for adjusting the same.

In the arrangement of parts shown in the drawings the convex guiding-surface E diverges from the center in both directions with relation to the opposed surface of the forwarder D, so that the cans may be fed in at either end of the machine. I do not confine myself, however, to this construction, the essential feature of my invention in this respect consisting in the use of a convex guiding-surface opposed to a flexible can-forwarding surface for presenting cans to the action of solder-removing devices when the convex guiding-surface is so arranged with relation to such solder-removing devices and to the flexible can-forwarding surface that the cans are successively and positively forced against the flexible can-forwarding surface by the convex guiding-surface, so as to insure effective contact therewith for the purpose of spacing the cans with relation to each other and sustaining them more effectually while subjected to the action of the solder-removing devices. In other words, I contract the space between the stationary can-guiding surface and the flexible can-forwarding surface to less than the diameter of the cans to be treated, and hence cause them to bend or deflect said flexible can-forwarding surface, even though the cans may vary slightly in shape or diameter as compared one with another. I thus obviate a difficulty heretofore encountered in the use of straight can-guiding surfaces parallel to the forwarding-surface, in which construction the cans are apt to collect or "bunch" in contact with each other by reason of the retarding tendency of the brushing mechanism or lack of accuracy in the size or shape of the cans under treatment. Thus by the substitution of the convex can-guiding surface in lieu of the straight parallel guide here-

tofore used I insure positive contact for each and every can introduced between the flexible forwarding-surface and the said guiding-surface, and in order to enable the flexible 5 forwarding-belt to adapt itself to any number of cans interposed between it and the convex guiding-surface it shall exert a uniform pressure on each and every can. I hold the forwarding-belt taut by means of an automatic tension device F of any suitable construction, that shown in the drawings consisting of an idler-pulley e, mounted in a yielding bearing e', actuated by a weight e² or equivalent mechanical expedient which 10 causes the idler-pulley e to take up any slack in the belt D, while yielding to allow the said belt to accommodate itself to the number of cans introduced between it and the convex guiding-surface E. The receiving end 15 of the convex guiding-surface E is formed with a spring-jaw e³, which projects eccentrically with relation to the forwarding belt-pulley d at that end of the machine. Where the machine is made reversible or right and 20 left handed, as shown in the drawings, both ends of the convex guide E are thus furnished with spring-jaws e³.

It will be seen that the brushing mechanism is situated centrally in the apparatus 30 with a fluid-blast O O' at either end, so that the end plate of the can is first subjected to a fluid-blast. Then the cylindrical edge of the can is brushed, and, finally, the end plate is again subjected to a fluid-blast. As a result the superfluous solder is first blown from 35 the end plate, a portion of the solder being carried onto the extreme edge of the can and even beyond the apex of the angle and onto the cylindrical flange of the end plate, from 40 which it is mainly dislodged by the brush, which latter, however, is apt to leave a slight bur or ridge of solder on said apex, to be removed by the final fluid-blast, which cleans and polishes the angle of the plate. 45 In order to insure this latter result, I use for the second fluid-blast a duplex nozzle G', (shown in detail in Fig. 2,) the jet g' being directed against the inner side of the end plate, while the jet g² is directed against the 50 angle of the flange thereof, insuring the displacement of all solder from the end of the can.

The cans are retarded and rotated while 55 subjected to the fluid-blasts by wheels H H', which are mounted in sliding bearings h h', so that they may be adjusted with relation to the convex guiding-surface for the purpose of increasing or diminishing the time during 60 which each can is submitted to the blast, the protrusion of the periphery of the retarding-wheel beyond said convex surface governing the surface to be surmounted and traversed by the can before its release from the retarding-wheel.

65 The sections B B' are mounted upon the shaft b, supported in end bearings b' b² and an intermediate bearing b³, which steadies

and centralizes the shaft against lateral strain during use. The said shaft is actuated by spiral gearing in the manner described in my 70 concurrent application, Serial No. 127,643, filed October 17, 1902. The sections of brush are inclosed when in use by covers a a, hinged to the main cover a', which closes the compartment a² within the base A. 75

The convex guiding-surface E is made adjustable with relation to the brushes and to the forwarding-surface D for the purpose of accurately defining the path of the cans by any suitable mechanical expedient, as by forming the bases e⁴ e⁴ of the supporting-standards e⁵ e⁵ with slots e⁶ e⁶, through which pass the adjusting-screws e⁷ e⁷, as shown in the drawings. The forwarding-belt D is also made adjustable with relation to the solder-removing mechanism and the convex surface for the purpose of adapting the apparatus to the treatment of cans of different diameters. This is accomplished by making the bearings 85 ii of the shafts I I adjustable upon the frame, 90 as shown by way of illustration in Fig. 13.

Upon the shafts I I are mounted the pulleys j j, which transmit motion by belts k k to the pulleys l l, by which the retarding-wheels H H are rotated. In order to compensate for 95 the adjustment of the shafts I I, I provide each belt k k with an automatic tension-regulator k' k' similar to that used for taking up the slack of the driving-belt D.

N is the stationary bottom rail for the support of the cans, and M the upper rail for confining the cans in position between the convex guiding-surface and the forwarding-belt. This upper rail M is adjustable vertically upon its standards to accommodate cans 105 of different lengths, as by means of the slotted brackets m m' and bolts m' m'. (Shown in Figs. 5, 6, and 7.)

What I claim as my invention, and desire to secure by Letters Patent, is—

1. In a solder-saving machine, mechanism for removing superfluous solder from cans, a convex guiding-surface for presenting the cans to said solder-removing mechanism, and a flexible forwarding-surface for feeding the cans along said convex guiding-surface, substantially as set forth.

2. In a solder-saving machine, mechanism for brushing superfluous solder from cans, a convex guiding-surface for presenting the cans to said brushing mechanism, and a flexible forwarding-surface for feeding the cans along said convex guiding-surface, substantially as set forth.

3. In a solder-saving machine, mechanism arranged to brush superfluous solder from the cylindrical edges of cans, a convex guiding-surface for the cylindrical bodies of the cans arranged to present the cylindrical edges of the cans to said brushing mechanism, and a flexible forwarding-surface for feeding the cans along said convex guiding-surface, substantially as set forth.

4. In a solder-saving machine, mechanism

for removing superfluous solder from cans, a convex guiding-surface for presenting the cans to such superfluous-solder-removing mechanism, a flexible forwarding-surface for feeding the cans along said convex guiding-surface, and supporting-rails for sustaining the cans against transverse movement upon and with relation to said convex guiding-surface, as set forth.

10 5. In a solder-saving machine, mechanism for brushing superfluous solder from cans, a convex guiding-surface for presenting the cans to said brushing mechanism, a flexible forwarding-surface for feeding the cans along said convex guiding-surface, and supporting-rails for sustaining the cans against transverse movement upon and with relation to the said convex guiding-surface and against the action of the brushing mechanism, substantially as set forth.

15 6. In a solder-saving machine, mechanism arranged to brush superfluous solder from the cylindrical edges of cans, a convex guiding-surface for the cylindrical bodies of the cans arranged to present the cylindrical edges of the cans along said convex guiding-surface, and supporting-rails for sustaining the cans against transverse movement upon and with relation to the said convex guiding-surface and against the action of the brushing mechanism, as set forth.

20 7. In a solder-saving machine, mechanism for removing superfluous solder from cans by means of a fluid-blast, a convex guiding-surface for conducting the cans to such fluid-blast, a flexible forwarding-surface for feeding the cans along said convex guiding-surface, and mechanism for retarding the cans temporarily while subjected to the action of the fluid-blast, substantially as set forth.

25 8. In a solder-saving machine, mechanism for removing superfluous solder from cans by means of a plurality of fluid-blasts, a convex guiding-surface for conducting the cans successively from one fluid-blast to another, a flexible forwarding-surface for feeding the cans along said convex guiding-surface, and mechanism for retarding the cans temporarily and successively at each of the said fluid-blasts, substantially as set forth.

30 9. In a solder-saving machine, mechanism for removing superfluous solder from cans by means of a fluid-blast, mechanism for brushing superfluous solder from cans, a convex guiding-surface for presenting the cans to both the fluid-blast and the brushing mechanism, and a flexible forwarding-surface for feeding the cans along said convex surface and past the fluid-blast and brushing mechanism, substantially as set forth.

35 10. In a solder-saving machine, mechanism for first subjecting the cans to the action of a fluid-blast for the purpose of removing superfluous solder and mechanism for subsequently brushing the cans for a like purpose, in combination with a convex guiding-surface for presenting the cans successively to said fluid-

blast and said brushing mechanism, together with a flexible forwarding-surface for feeding the cans along said convex guiding-surface and to the solder-removing devices named, substantially as set forth.

40 11. In a solder-saving machine, mechanism for brushing off superfluous solder from cans and for subsequently subjecting the cans to the action of a fluid-blast for a like purpose, in combination with a convex guiding-surface for presenting the cans successively to both the brushing mechanism and the fluid-blast, together with a flexible forwarding-surface for feeding the cans along said convex guiding-surface and to the solder-removing devices named, substantially as set forth.

45 12. In a solder-saving machine, mechanism for first subjecting the cans to the action of a fluid-blast, then to the action of brushing mechanism, and then to the action of another fluid-blast for the purpose of removing superfluous solder from the cans, in combination with a convex guiding-surface for presenting the cans successively to said solder-removing devices, together with a flexible forwarding-surface for feeding the cans along said convex guiding-surface, substantially as set forth.

50 13. In solder-saving apparatus, the combination of mechanism for first subjecting the cans to the action of a fluid-blast and then to the action of brushing mechanism, a convex guiding-surface and a flexible forwarding-surface for conveying the cans to and from said fluid-blast and brushing mechanism, and means for adjusting the said convex guiding-surface with relation to the said fluid-blast and brushing mechanism, substantially as and for the purpose described.

55 14. In a solder-saving machine, mechanism for first subjecting the cans to the action of a fluid-blast, then to the action of brushing mechanism, and then again to the action of a fluid-blast for the purpose of removing superfluous solder from the cans, together with means for conveying the cans to and from said solder-removing devices, substantially as set forth.

60 15. In solder-saving apparatus, the combination of mechanism for first subjecting the end plate of a can to a fluid-blast arranged to remove superfluous solder from said end plate and then to the action of brushing mechanism arranged to remove superfluous solder from a cylindrical end of the can, a convex guiding-surface and a flexible forwarding-surface for conveying the cans to and from said fluid-blast and brushing mechanism, and means for adjusting said convex can-guiding surface with relation to the said fluid-blast and the said brushing mechanism, substantially as and for the purpose set forth.

65 16. In a solder-saving machine, mechanism for first subjecting the end plate of a can to a fluid-blast arranged to remove superfluous solder from said end plate, then to the action of brushing mechanism, for removing super-

fluous solder from a cylindrical edge of the can and then to the action of another fluid-blast arranged to clean and polish the end plate after the action of the brush, together with means for conveying the cans to and from said solder-removing devices, substantially as set forth.

17. In a solder-saving machine, mechanism for first subjecting the end plate of a can to a fluid-blast arranged to remove superfluous solder from said end plate, and then to the action of brushing mechanism arranged to remove superfluous solder from a cylindrical end of the can, in combination with a convex guiding-surface and an opposed flexible forwarding-surface arranged and acting in conjunction to present the cans successively to the action of said solder-removing devices, substantially as set forth.

18. In a solder-saving machine, mechanism for first subjecting the end plate of a can to a fluid-blast arranged to remove superfluous solder from said end plate, then to the action of brushing mechanism arranged to remove superfluous solder from a cylindrical end of the can and next to a supplementary fluid-blast arranged to clean and polish the end plate after the action of the brush, in combination with a convex guiding-surface and an opposed flexible forwarding-surface arranged and acting in conjunction to present the cans successively to the action of the said solder-removing devices, substantially as set forth.

19. In a solder-saving machine, a plurality of brushes for removing superfluous solder from the cylindrical edges of cans, in combination with a convex guiding-surface and an opposed flexible forwarding-surface arranged and acting in conjunction to present the cans successively to the action of the said plurality of brushes, substantially as set forth.

20. In a solder-saving machine, mechanism for brushing superfluous solder from cans, a convex guiding-surface for presenting the cans to said brushing mechanism, said convex guiding-surface being arranged in proximity to the brushing mechanism, and a flexible forwarding-surface opposed to said brushing mechanism and to the said convex guiding-surface, and arranged to feed the cans along said convex surface and against the brushing mechanism, substantially as set forth.

21. In a solder-saving machine, a substantially horizontal supporting-rail, a substantially vertical convex guiding-surface, a substantially vertical forwarding-surface, and solder-removing mechanism arranged to treat the cans forwarded on end on said supporting-rail by and between the said convex guiding-surface and said flexible forwarding-surface, substantially as set forth.

22. In a solder-saving machine, a substantially horizontal supporting-rail, a substantially vertical convex guiding-surface, a substantially horizontal brushing mechanism for removing superfluous solder from the cans, and a substantially vertical flexible forward-

ing-surface opposed to said convex guiding-surface and arranged to feed the cans over said convex guiding-surface and against the brushing mechanism, substantially as set forth.

23. In a solder-saving machine, a rigid convex can-guiding surface and an opposed flexible can-forwarding surface consisting of an endless belt, together with mechanism for removing superfluous solder from the cans forwarded over said convex guiding-surface by the said flexible forwarding-belt, substantially as set forth.

24. In a solder-saving machine, a rigid can-supporting rail, a rigid convex can-guiding surface and an opposed flexible can-forwarding surface consisting of an endless belt, in combination with mechanism for removing superfluous solder from the cans forwarded over said supporting-rail and said convex guiding-surface by the said flexible forwarding-belt, substantially as set forth.

25. In a solder-saving machine, a rigid convex can-guiding surface and an opposed flexible can-forwarding surface consisting of an endless belt, in combination with brushing mechanism arranged to remove superfluous solder from cans forwarded over said convex guiding-surface by said endless belt, substantially as set forth.

26. In a solder-saving machine, a rigid convex can-guiding surface and an opposed flexible can-forwarding surface consisting of an endless belt, in combination with means for directing a fluid-blast against the cans forwarded over said convex guiding-surface for the purpose of removing superfluous solder from said cans, substantially as set forth.

27. In a solder-saving machine, a rigid convex can-guiding surface and an opposed flexible can-forwarding surface consisting of an endless belt, in combination with means for directing a fluid-blast against the cans forwarded over said convex guiding-surface for the purpose of removing superfluous solder from said cans, and means for retarding and rotating said cans successively while subjected to the action of the said fluid-blast, substantially as set forth.

28. In a solder-saving machine, a rigid convex can-guiding surface and an opposed flexible can-forwarding surface consisting of an endless belt, in combination with can-brushing mechanism and means for directing a fluid-blast against the cans forwarded over said convex guiding-surface whereby superfluous solder is brushed and blown from the exterior surfaces of said cans, substantially as set forth.

29. In a solder-saving machine, a rigid convex can-guiding surface and an opposed flexible can-forwarding surface consisting of an endless belt, in combination with brushing mechanism arranged to remove superfluous solder from the cylindrical edges of cans forwarded over said convex guiding-surface, means for retarding and rotating the cans

successively as they are forwarded by said endless belt, and means for directing a fluid-blast against the end plate of a can so retarded and rotated for the purpose of removing superfluous solder from the end plate of said can, substantially as set forth.

30. In a solder-saving machine, mechanism for removing superfluous solder from cans, a convex guiding-surface for presenting the cans to such solder-removing mechanism, a flexible forwarding-surface for feeding the cans along said convex guiding-surface, and means for regulating the tension of said flexible can-forwarding surface, substantially as set forth.

31. In a solder-saving machine, mechanism for removing superfluous solder from cans, a convex guiding-surface for presenting the cans to such solder-removing mechanism, of an endless belt for feeding the cans along said convex guiding-surface, and means for regulating the tension of said belt for the purpose and substantially as set forth.

32. In a solder-saving machine, mechanism for removing superfluous solder from cans, a convex guiding-surface for presenting the cans to such solder-removing mechanism, an endless belt for feeding the cans along said convex guiding-surface, and means for automatically regulating the tension of the said belt, for the purpose described.

33. In a solder-saving machine, mechanism for removing superfluous solder from cans, a convex guiding-surface for presenting the cans to such solder-saving mechanism, an endless belt for feeding the cans along said convex guiding-surface, an idler-pulley engaging said forwarding-belt, and means for pressing said idler-pulley against said belt with a yielding pressure, whereby the belt automatically adapts itself to the number of cans passing over said convex guiding-surface, substantially as set forth.

34. In a solder-saving machine, mechanism for removing superfluous solder from cans, a convex guiding-surface for presenting the cans to such solder-saving mechanism, an endless belt for feeding the cans along said convex surface, and a suspended weight and connections arranged to hold the said belt to a uniform degree of pressure, substantially as set forth.

35. In a solder-saving machine, mechanism for removing superfluous solder from cans, a convex guiding-surface for presenting the cans to such solder-saving mechanism, an endless belt for feeding the cans along said convex guiding-surface, an idler-pulley engaging said forwarding-belt and mounted in a sliding bearing, and a suspended weight secured to said sliding bearing, whereby the belt is made to automatically adapt itself to the number of cans upon the said convex guiding-surface and to exert a uniform pressure upon the cans irrespective of the number thereof, substantially as set forth.

36. In a solder-saving machine, mechanism

for removing superfluous solder from cans, a convex guiding-surface for presenting the cans to said solder-removing mechanism, a flexible forwarding-surface for passing the cans over said convex guiding-surface and means for adjusting said flexible can-forwarding surface with relation to said convex guiding-surface, for the purpose set forth.

37. In a solder-saving machine, mechanism for removing superfluous solder from cans, a convex guiding-surface for presenting the cans to said solder-removing mechanism, a flexible forwarding-surface consisting of an endless belt arranged to pass the cans over said convex guiding-surface, and means for adjusting said endless belt with relation to the said convex guiding-surface, for the purpose set forth.

38. In a solder-saving machine, mechanism for brushing superfluous solder from cans, a convex guiding-surface for presenting the cans to said brushing mechanism, a flexible forwarding-surface consisting of an endless belt arranged to pass the cans over said convex guiding-surface and in contact with said brushing mechanism, and means for adjusting said endless belt with relation to said convex guiding-surface and said brushing mechanism, substantially as set forth.

39. In a solder-saving machine, mechanism for removing superfluous solder from cans, a convex guiding-surface for presenting the cans to said solder-removing mechanism, a flexible forwarding-surface for passing the cans over said convex guiding-surface, and means for adjusting said convex guiding-surface with relation to the said solder-removing mechanism, for the purpose set forth.

40. In a solder-saving machine, mechanism for removing superfluous solder from cans, a convex guiding-surface for presenting the cans to said solder-removing mechanism, a flexible forwarding-surface for passing the cans over said convex guiding-surface, and means for adjusting said convex guiding-surface with relation to said flexible can-forwarding surface, substantially as described.

41. In a solder-saving machine, mechanism for brushing superfluous solder from cans, a convex guiding-surface for presenting the cans to said brushing mechanism, a flexible forwarding-surface for passing the cans over said convex guiding-surface and in contact with the brush, and means for adjusting said convex guiding-surface with relation to said brushing mechanism, substantially as set forth.

42. In a solder-saving machine, means for projecting a fluid-blast against the end plate of a can, a convex guiding-surface for conducting the cans to said fluid-blast, an opposed flexible forwarding-surface for advancing the cans over said convex guiding-surface, a wheel opposite said fluid-blast arranged to retard and rotate each can while the latter is subjected to the fluid-blast and means for adjusting said retarding-wheel

with relation to said convex guiding-surface and said flexible can-forwarding surface, substantially as set forth.

43. In a solder-saving machine, mechanism for removing superfluous solder from cans, a convex guiding-surface for presenting the cans to said solder-removing mechanism, a flexible forwarding-surface for passing the can along said convex guiding-surface, said convex guiding-surface being formed with a spring-jaw at its receiving end for guiding the cans in between said flexible forwarding-surface and the said convex guiding-surface, substantially as set forth.

44. In a solder-saving apparatus, mechanism for removing superfluous solder from cans, a stationary convex guiding-surface for presenting the cans to the said solder-removing mechanism, and a flexible forwarding-surface consisting of an endless belt arranged to pass the cans over said stationary convex guiding-surface in either direction to and from said solder-removing mechanism, according to the direction in which said flexible forwarding-surface is made to travel, for the purpose and substantially in the manner described.

45. In a solder-saving machine, mechanism for removing superfluous solder from cans consisting of brushing mechanism interposed between two fluid-blasts, a convex guiding-surface for presenting the cans to said solder-removing mechanism, and an endless belt arranged to forward the cans over said convex guiding-surface in either direction, substantially as set forth.

46. In solder-saving apparatus, the combination of mechanism for removing superfluous solder from cans, a stationary convex guiding-surface for presenting the cans to said solder-removing mechanism, a flexible can-forwarding surface, means for adjusting said can-forwarding surface with relation to said stationary convex guiding-surface, and a can-retaining rail which is adjustable with relation to the solder-removing mechanism for the purpose of adapting the apparatus to more than one size of can, substantially as set forth.

47. In solder-saving apparatus, the combination of an elongated brush for removing superfluous solder from cans, said brush being made in two sections mounted upon the same shaft, a stationary convex guiding-surface for presenting the cans to the said sectional brush and a flexible forwarding-surface consisting of an endless belt arranged to pass the cans over said stationary convex guiding-surface in either direction to and from said sectional brush according to the directions in which said flexible forwarding-surface is made to travel, for the purpose and substantially in the manner described.

48. In a solder-saving machine, the combination with a stationary convex guiding-surface, and with a flexible can-forwarding surface consisting of an endless belt, of an elongated brush arranged in proximity to the said convex guiding-surface, and substantially parallel thereto, said elongated brush being made in two sections mounted upon the same shaft, with a shaft-bearing between them in addition to the end bearings of the shaft, whereby the alinement of both sections of the brush is insured with relation to the said convex can-guiding surface, and the said opposed can-forwarding surface, substantially as set forth.

49. In a solder-saving machine, the combination with a stationary can-guiding surface, and with an endless belt for forwarding cans over said stationary guiding-surface, of an elongated brush arranged parallel to said stationary guiding-surface and said forwarding-belt, said elongated brush being made in two sections mounted upon the same shaft with a shaft-bearing between them in addition to the end bearings of the shaft, whereby the perfect alinement of both sections of the brush is maintained, substantially as and for the purpose herein set forth.

50. In a solder-saving machine, the combination with a stationary can-guiding surface, and with an endless belt for forwarding cans over said stationary guiding-surface, of an elongated brush arranged substantially parallel to said stationary guiding-surface and said forwarding-belt, said elongated brush being made in two sections mounted upon the same shaft with a shaft-bearing between them in addition to the end bearings of the shaft, and each section of the brush being inclosed by a cover for the purpose and substantially in the manner set forth.

51. In solder-saving apparatus the combination of can forwarding and retarding mechanism, and two jets arranged to simultaneously project fluid under pressure radially against the edge of an end plate of a can the one jet causing the fluid under pressure to impinge against the inner edge of the end plate, and the other jet causing the fluid under pressure to impinge against the apex of the edge of the can end plate where the latter is bent over upon the can-body for the purpose and substantially in the manner set forth.

52. In solder-saving apparatus, the combination of can forwarding and retaining mechanism and a nozzle formed with two convergent nipples arranged to simultaneously project fluid under pressure radially against the edge of an end plate of a can, the one nipple directing the fluid under pressure radially against the inner edge of the can-plate, and the other nipple directing the fluid radially under pressure against the apex of the edge of the can end plate where the latter is bent over upon the can-body, for the purpose and substantially in the manner set forth.

53. In solder-saving apparatus, the combination of mechanism for removing superfluous solder from cans, a stationary guiding-surface for presenting cans to said solder-removing mechanism, and a flexible forward-

ing-surface for feeding the cans along said stationary guiding-surface to and from the solder-removing mechanism, said flexible forwarding-surface being arranged to travel in 5 a line convergent to said stationary guiding-surface, whereby the cans are all positively held by and between the said stationary guid-

ing-surface and flexible forwarding-surface, substantially as set forth.
